UNITED STATES PATENT OFFICE

2,684,756

CANTEEN OR MESS KIT

Charles Belsky, Detroit, Mich.

Application January 25, 1951, Serial No. 207,717

6 Claims. (Cl. 206—4)

1

This invention relates to canteens or mess kits. Broadly the invention comprehends a canteen or mess kit wherein the component parts are so related and connected that they may be folded upon one another so as to occupy but small space and also to provide a sealed or closed container suitable for the reception of implements and/or rations.

An object of the invention is to provide a canteen including two or more containers so constructed and connected that they may be folded together to provide a closed compartment and when opened may be supported by a unitary handle, which also provides a closing means for the containers and means for retaining the containers in closed position.

Another object of the invention is to provide a canteen having two containers and a unitary handle so made and arranged that the handle serves to support both containers when the canteen is open and to lock the containers together when the canteen is closed.

Yet another object of the invention is to provide a canteen having but few component parts which may be easily and quickly produced and assembled so that its manufacture may be attained at the minimum cost.

Other objects and advantages of the invention will appear from the following description when taken in connection with the drawings forming a part of this specification and in which:

Fig. 1 is a top plan view of a canteen embodying the invention.

Fig. 2 is an end view of the canteen when closed.

Fig. 3 is a side elevation of the canteen when closed with the handle shown in dotted lines before it is folded.

Fig. 4 is a side elevational view illustrating the handle as folded but not secured against displacement.

Fig. 5 is an enlarged fragmentary view illustrating the relation of the handle to the canteen when closed.

Fig. 6 is a top plan view of the hinge for joining the individual containers of the canteen.

Fig. 7 is a top plan view of the canteen in open position.

Fig. 8 is a cross sectional view of the handle taken on line 8—8 of Fig. 7, and

Fig. 9 is a fragmentary sectional view taken substantially on line 9—9 of Fig. 7.

Referring to the drawings for more specific details of the invention, 2 indicates a pan or container preferably oval in general contour. The rim of the container is deformed to provide

2

a marginal flange 4 bent back and under upon itself as indicated at 6 to lend strength and rigidity to the structure, and the flange has a continuous groove 8, the purpose of which will herein-
5 after appear.

A corresponding pan or container constituting a cover 10 is secured to one side of the pan 2 as by a hinge 12, the pintle of which is extended and deformed to provide a ring and/or hook for 10 suspension of the canteen, and the rim of the container has a rolled edge 16 adapted to fit snugly in the continuous groove 8 in the flange 4 of the container 2 so as to effectively seal the pans and/or containers together when in the folded or closed position.

A handle indicated generally at 18 includes two corresponding parts 20 and 22, each having an off-set portion 24 and 26 deformed to provide a hinge 28 serving to pivotally join the parts 20 20 and 22. The handle has a flared butt 30 provided with a lateral tongue 32, the purpose of which will hereinafter appear, and oppositely curved shanks 34 and 36 pivotally secured as by hinges 38 and 40 to the pans 2 and 10 and the handle and shanks have ribs 42 serving to lend strength and rigidity thereto.

When the canteen is open as illustrated in Fig. 7, the pans and/or containers 2 and 10 may be used as cooking utensils or as containers for the reception of food or rations and in whatever use both pans or containers are supported by a unitary handle.

When it is desired to close the canteen, the pan 10 constituting the cover is swung on the hinge 12 connecting the pans 2 and 10 and concomitantly therewith the part 22 of the handle is swung on the hinge 28 connecting the parts 20 and 22 of the handle. When the pans are folded together the rolled rim 16 on the pan 10 fits snugly in the groove 8 in the flange 4 of the pan 2, and the part 22 of the handle is immediately above the part 20 of the handle. When in this position the axes of the hinges 38 and 40 are in alignment. The handle is then swung on the hinges 38 and 40 against the pans and when in this position, the hinge 28 opposes the hinge 12 and this effectively locks the pans together. Preferably the axes of the hinges 38 and 40 are slightly inclined so that the handle 18 when folded is slightly off the horizontal axis of the pans, and when in this position, the handle may be sprung so that the tongue 32 may be firmly held against the back of the rolled rim 16 of the pan 10.

While I have shown and described the preferred embodiment of my invention, I wish it to

be understood that I do not confine myself to the precise details of construction herein set forth, by way of illustration, as it is apparent that many changes and variations may be made therein by those skilled in the art, without departing from the spirit of the invention or exceeding the scope of the appended claims.

Having thus described the invention, what I claim as new and desire to secure by Letters Patent is:

1. A canteen comprising matched containers, a hinge connecting the containers to fold one upon the other, and a handle for the canteen including like sections contoured to flap against the containers and hinges connecting the sections to one another and to the respective containers so pivoted as to swing one above the other and fold against the containers.

2. A canteen comprising matched containers, a hinge having a pintle connecting the containers to fold one upon the other, a hook contiguous with the pintle, a handle for the canteen including corresponding parts, hinges connecting the parts to one another and to the respective containers so pivoted as to swing one above the other and fold against the containers.

3. A canteen comprising matched containers, means pivotally connecting the containers so as to fold one upon the other and a handle for the canteen including like sections contoured to fit against the walls of the containers, means pivotally connecting the sections to the respective containers and means pivotally connecting the sections to one another in axial alignment with the pivotal connection of the containers, said sections to swing one above the other and against the containers when the containers are folded one upon the other.

4. A canteen comprising matched containers, means hinging the containers together so as to fold one upon the other and a handle for the container including corresponding members, means hinging each member to a separate container and

means hinging the members together in axial alignment with the hinge connecting the containers.

5. A canteen comprising matched containers, means pivotally connecting the containers substantially centrally of the length of the containers, a handle for the canteen including corresponding members, means hinging each member to a separate container and means hinging the members together at a point removed from the containers and in axial alignment of the hinge of the containers, and a clip on one of the members for locking the handle in folded position against the containers.

10 6. A canteen comprising matched containers having complementary rims, means pivotally connecting the containers so as to fold one upon the other and a handle for the canteen including like members contoured to flap against the walls of the containers, means pivotally connecting each member to a separate container and means pivotally connecting the members together at a distance removed from the containers and in axial alignment with the pivotal connection of the containers and a lateral tongue on one of the members cooperating with the rim of one of the containers for locking the handle in folded position.
